UNITED STATES PATENT OFFICE.

EDWIN D. VALLIANT, OF SAN MARTIN, CALIFORNIA.

DEHYDRATOR.

Application filed June 21, 1921. Serial No. 479,214.

To all whom it may concern:

Be it known that I, EDWIN D. VALLIANT, a citizen of the United States, and a resident of San Martin, in the county of Santa Clara and State of California, have invented certain new and useful Improvements in Dehydrators, of which the following is a specification.

This invention relates particularly to a machine for use in dehydrating fruits such as prunes and apricots but may be utilized for the drying of nuts or treatment of vegetables.

It is the object of my invention to provide a dehydrator that will readily accommodate a large quantity of material, and in which all or any part of the material may be easily inspected at any time. It is a further object to provide a dehydrator in which the material placed therein will be uniformly subjected to the action of the drying air, and in which the air flow may be so directed, tempered, and controlled as to prevent case hardening of the fruit and secure a progressively uniform drying thereof. In this invention I provide a new and novel means of securing a complete and effective circulation of the air throughout the entire dehydration-chamber. Finally, it is an object of the invention to provide a machine of the character indicated that will be simple in form, compact, economical in construction and operation, and highly efficient in its practical application.

In the drawing:

Figure 1 is a vertical section through the center of the machine.

Figure 2 is a detail section on line 2—2 of Figure 1.

Figure 3 is a sectional view on line 3—3 of Figure 1 part broken away.

Figure 4 is an enlarged plan view of the vane adjusting device.

Figure 5 is a reduced elevation of the complete dehydration plant.

Referring more particularly to the drawing, 1 indicates a circular foundation of suitable dimensions carrying a perpendicular wall 2 to form a dehydration chamber 3 in conjunction with ceiling 4, and having a roof 5 with an air discharge outlet 6. The ceiling 4 is carried on brackets 7 mounted on wall 2 and is of less diameter than said wall whereby to provide an annular passage therebetween for the outflow of the moist dehydration air. At 8 is shown a door slid-

ably mounted in wall 2, and at 9 a pocket to receive the door when opened.

At 10 is shown a pit in the center of the chamber 3, and at 11 is a heated air conduit through which heated air is discharged into the pit by means of a suitable fan at 12, the heated air being drawn from a heater 13 (see Fig. 5). On the top of the pit 10 is mounted an annular casting 14 on ball bearings 15, said casting having a shoulder 16 formed on the exterior thereof, an air passage 17 formed therein and a groove 18 formed in its upper edge, the shoulder 16 being hexagonal in form as shown in Fig. 3.

On shoulder 16 are arranged six joists 19 extending therefrom to a point adjacent wall 2. Upon the corresponding sides of each joist are arranged a pair of parallel spaced joists as 20 and 21 extending outwardly the same distance as joists 19, all of the joists being covered with a flooring 22 and each joist having a roller 23 mounted thereon. The rollers 23 are arranged in a circle to run on a track 24 set in the bottom of the chamber 3. The table thus formed may be rotated in any suitable manner as by an annular gear 25 mounted on the underside thereof having gear connections to a motor 26 arranged on the exterior of the chamber and controlled by a lever 27.

On flooring 22 and directly over joists 20 and 21 are placed beams 28 carrying vertical bars 29, the bars 29 being spaced apart substantially the width of the trays 30, and beams 28 being slightly closer together to form a support for a stack of trays. In the present case I show two stacks of trays on each set of beams, each stack being run into position on a truck, lowered onto beams 28 and the truck removed. By means of this construction the stacks of trays are placed in the several compartments A to L inclusive, the intermediate spaces 31 being utilized for inspection of the fruit.

Axially arranged in chamber 3 and supported on a thrust bearing 32 in pit 10 is a vertical shaft 33 having also a bearing at its upper end at 34. Rigidly mounted on shaft 33 by brackets 35 is a conduit 36 extending downwardly into groove 18 so as to prevent any material amount of air from issuing at this point and yet permitting the free revolution of said conduit. The conduit 36 is here shown as branching laterally four ways at its upper end as at 37—37^a—37^b—37^c and about midway the height of

chamber 3, each branch having a pipe section as 38 adjustably mounted thereon by adjusting and supporting brackets 39. Pipe 38 is flattened out to form a long narrow discharge nozzle 40 having its mouth arranged parallel with shaft 33 and spaced a little way from the inner ends of trays 30 as shown. At 41 is shown a diffusion vane adjustably mounted at the end of nozzle 40 in the relative position shown. The adjustment is effected by means of a bracket 42 mounted on each end of nozzle 40 and provided with a curved slot 43, the vane carrying bars 44 provided with orifices 45 and bolts 46. By means of this construction the vanes may be placed close to the nozzle 40 or spaced a distance therefrom at either end, and it may be placed at any desired angle to the normal air flow 20 through said nozzle.

Passing upwardly from the center of conduit 36 is a conduit 47 having an opening 49 into the space 48 between ceiling 4 and roof 5, this opening being controlled by a valve 50 hinged at 51 and operated by a rod 52. At 53 is shown another conduit communicating with conduit 47 and heater 13, the valve 50 closing this conduit when opening passage 49 and vice versa.

In conduit 36 are provided a number of small orifices as 54, for the purpose herein-after described.

In loading the dehydrator the trays are trucked into and deposited in one compartment as A, the lever 27 being operated to revolve the table as described thereby bringing compartment B into alignment with the door. Each of the remaining compartments are now successively brought into position and loaded, upon which the door 40 is closed.

The fan being started, heated air is driven through conduits 11, 17, and 36 out through nozzles 40 into chamber 3 and impinging upon the several vanes. The vanes being set to direct the air from all of the nozzles in the same direction, the reaction causes shaft 33 and all the parts mounted thereon to revolve, thereby securing a thorough and uniform distribution of the air through and around all of the trays 30.

The air discharged into chamber 3 is driven out into space 48 and thence to the atmosphere. Since the air from nozzles 40 is driven outwardly to the circumference of the chamber 3 there is a suction created at the upper and lower ends of the revolving nozzles tending to create an air circulation such as indicated by arrows 55. Air circulating in this manner would fill the center of the chamber with moist air and interfere somewhat with the successful operation of the dehydrator. To obviate this difficulty I provide several small orifices in conduit 36 so that a small amount of warm dry air

is being constantly fed into the center of the chamber and the undesired flow of air above referred to eliminated.

By opening valve 50 in conduit 47, to close conduit 53, the air will be discharged 70 direct into chamber 48. If the air is not sufficiently heated, then the valve 50 is opened with respect to conduit 53 and closes opening 49 so that a quantity of heated air is drawn from conduit 36 through conduits 75 47 and 53 to be reheated to a higher temperature in heater 13 and again mixed with dehydration air and passed through conduit 11. Valve 50 is shown as a double leaf valve, one leaf as 50^a being operable by a 80 separate rod 50^b so that both opening 49 and conduit 53 may be closed at the same time when no variation in the temperature of the dehydration air is desired.

I claim:—

1. A dehydrator comprising a dehydration chamber, means for supporting material to be dehydrated therein, an air supply conduit revolvably mounted in the center of said chamber, means for supplying air to 90 said conduit, means for discharging the air radially from said conduit, and means in the path of the radially discharging air for revolving said conduit.

2. A dehydrator comprising a dehydration chamber, means for supporting material to be dehydrated therein, an air supply conduit revolvably mounted in said chamber, an air duct extending radially from said conduit, a nozzle on said duct, and means 100 for directing the air discharge from said nozzle at an angle to the radial plane of said air duct whereby to effect the rotation of said duct and conduit.

3. A dehydrator comprising a dehydration chamber, means for supporting material to be dehydrated therein, an air supply conduit revolvably mounted in said chamber, an air duct extending radially from said conduit, a discharge nozzle on said duct, and 110 an air deflection vane arranged on said nozzle for directing the air discharge to effect rotation of said conduit.

4. A dehydrator comprising a dehydration chamber, means for supporting material to be dehydrated therein, an air supply conduit revolvably mounted in said chamber, an air duct extending radially from said conduit, a discharge nozzle on said duct, and 120 an air deflection vane arranged on said nozzle in the path of the discharging air and rotatably adjustable about a vertical axis adjacent said nozzle.

5. A dehydrator comprising a dehydration chamber, an air supply conduit revolvably mounted in the chamber, means for supplying air to said conduit, means for supporting material to be dehydrated about the conduit, discharge nozzle connected to 125 said conduit to revolve therewith adjacent 130

said material and having a vertically disposed discharge orifice extending to points adjacent the top and bottom of said chamber, and means carried by the nozzle for deflecting the air from said nozzle orifice to effect rotation of the conduit.

6. A dehydrator comprising a dehydration chamber, an air supply conduit revolvably mounted in the chamber, means for supplying air to said conduit, means for supporting material to be dehydrated about the conduit, and a nozzle operatively mounted on said conduit to discharge air therefrom toward the surrounding wall of the chamber, said conduit having means for introducing a quantity of air into said chamber between the axis thereof and the path of travel of said nozzle.

7. A dehydrator comprising a dehydration chamber designed for supporting a series of trays, means for supplying a drying current of air thereto, and a distributing device comprising a rotatably mounted series of radiating nozzles having orifices for directing the drying air in a direction substantially tangential to the path of movement of the nozzles whereby to effect rotation of said nozzles.

8. A dehydrator comprising a dehydration chamber, means for supporting material to be dehydrated therein, an air discharge chamber arranged over said dehydration chamber and communicating therewith adjacent the circumference, an air supply conduit revolvably mounted in said chamber, an air nozzle operatively mounted thereon to direct the air radially toward the circumference of said chamber, and a valve

controlled air conduit communicating with said revoluble conduit and said air discharge chamber for controlling the discharge of air from the nozzle.

9. A dehydrator comprising a dehydration chamber, means for supplying a drying current of air thereto, and a series of radiating distributing nozzles connected to the aforesaid means, deflecting vanes mounted on the nozzles in the path of the discharging air, and means for adjusting the vanes relative to the nozzles.

10. A dehydrator comprising an annular dehydration chamber having a door therein, a floor revolvably mounted therein, a plurality of radially arranged compartments arranged on said floor, means for operating said floor to bring any desired compartment in alignment with said door, means for supporting a plurality of trays in each compartment, and means within the circular series of compartments for distributing a continuous flow of air thru said chamber and the compartments therein.

11. A dehydrator comprising a dehydration chamber, means for supplying a drying current of air thereto, a plurality of radiating distributing nozzles connected to said means and rotatably mounted, and means adjustably carried by the nozzles to effect a discharge of air therefrom at a variable angular relation to the radial planes including the nozzles for varying the speed of rotation of the same, said nozzles being rotated by and during the discharge of air therefrom.

EDWIN D. VALLIANT.
